UNITED STATES PATENT OFFICE.

RUSSELL R. WATERMAN, OF LONG BEACH, CALIFORNIA, ASSIGNOR TO FARMERS' NATIONAL BANK OF GREENVILLE, OHIO, OF GREENVILLE, OHIO, A CORPORATION OF OHIO, TRUSTEE.

BALANCED THROTTLE VALVE FOR STEAM-POWER PLANTS.

Application filed May 17, 1926. Serial No. 109,567.

My invention relates to a balanced throttle valve for a steam line from the boiler to the engine in steam power plants, and the objects of my invention are: first, to provide a 5 throttle valve so constructed and arranged that the steam pressure from the boiler on the valve is balanced, permitting easy operation of the throttle valve; second, to provide a throttle valve so constructed that the back 10 pressure from the engine is balanced; third, to provide a throttle valve that is practically leak proof; fourth, to provide a throttle valve that is easy to take apart for repairs; and, fifth, to provide a throttle valve of this class 15 which is very simple and economical of construction, easy to install or remove, efficient in its action and which will not readily deteriorate or get out of order.

With these and other objects in view as will 20 appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a vertical sectional view 30 through my throttle valve, showing some of the parts and portions in elevation to facilitate the illustration, and Fig. 2 is a transverse sectional view taken on line 2-2, Fig. 1.

Similar characters of reference refer to 35 similar parts and portions throughout the different views of the drawings.

The casing 1, casing head 2, stuffing box 3, valve stem 4, valve member 5, piston 6 and valve seat member 7 constitute the principal 40 parts and portions of my balanced throttle valve.

From one side of the casing 1, which is preferably cylindrical, extends a boss 13. This boss has a bore 14 through which the 45 steam passes to the engine. One end of the casing 1 is provided with the casing head 2 into which is screwed or otherwise secured the steam conduit 15 from the boiler. To the opposite end of the casing 1 is attached the 50 stuffing box 3. A bore 16 extends transversely through the casing 1 in which is reciprocally mounted the valve stem 4 which extends out through the stuffing box 3. The bore 16 is

provided with an enlargement 17 in which is reciprocally mounted the piston 6 having 55 grooves on its outer face to facilitate the steam seal. Further enlargement 18 is made of enlargement 17 to provide space for the valve seat member 7 which is provided with grooves on its outer face to facilitate the 60 steam seal. The valve seat member 7 is so shaped as to provide two valve seats, one at point 8 and one at point 19, and between the two valve seats is provided a chamber 9. The valve 5 is integrally attached to the end 65 of valve stem 4 and is provided with the tapered portion 12 which comes in contact with valve seat member 7 at point 19 and with a still larger portion 20 which comes in contact with valve seat member 7 at point 8. 70 Bores 10, 10^a and 10^b are connected so as to provide one passage for steam. Bore 10 opens on one side of the valve 5 and into the chamber 9. Bore 10^b opens on one side of the valve stem 4 into the cylindrical bore 11. 75 Through the center of the tapered portion of the valve 12 and through the valve stem 4, between the bores 10 and 10^b, is an orifice 10^a.

When the valve 5 is opened the seal at the point 8 is broken permitting steam to enter 80 the chamber 9, through which steam passes through bores 10, 10^a and 10^b, entering the cylindrical bore 11. The cross-sectional area of the piston 6 minus the area of the valve stem 4 is approximately equal to the cross- 85 sectional area of the largest part of the tapered portion 12 of the valve 5. When the sealing point 8 is broken, the tapered portion 12 takes up the throttling, consequently the boiler pressure is upon the tapered portion 90 12. But due to steam entering the cylindrical bore 11, the boiler pressure upon the piston 6 is approximately equal to that upon the tapered portion 12 resulting in a balanced pressure.

Likewise the back pressure from 95 the engine is approximately equal upon the piston 6 and the tapered portion 12. Thus the pressure from the boiler and the back pressure from the engine are both balanced which permits of very easy operation of the 100 throttle valve.

Though I have shown and described a particular construction, combination and arrangement of parts and portions, I do not wish to be limited to this particular construction, combination and arrangement but de- 105

sire to include in the scope of my invention the construction, combination and arrangement substantially as set forth in the appended claims.

5 Having thus described my invention, what I claim as new and desire to secure by Letters Patent is:

1. In a device of the class described, a casting provided with a bore therein and with 10 inlet and outlet means in connection with said bore, a valve reciprocally mounted in said bore on one side of said outlet means, a piston on the opposite side of said outlet means connected to and of approximately the same 15 diameter as said valve, a conduit means extending from and to the spaces at the remote sides of said valve and piston relative to each other, said conduit means communicating with said bore, and a valve of larger diameter 20 than the first valve secured to said first valve, there being provided a steam chamber in the bore between the seats of said valves, said conduit means being in communication with said steam chamber.
2. In a balanced throttle valve for steam engines, a casing provided with two valve seats of different diameters said casing having an outlet at one side of the valve seats and an inlet at the opposite sides thereof and also 30 provided with a steam chamber positioned between the two valve seats, a valve, with two seat portions mounted thereon reciprocally mounted in said casing adapted to engage the two seats in said casing, said valve having a 35 stem, a piston mounted on the valve stem and reciprocally mounted in said casing at the side of the outlet opposite said valve seats, and a bore in said valve and stem extending from the steam chamber to the space on the side of 40 the piston farthest from the valve.
3. In a throttle valve for steam engines, a casing provided with bores of two different diameters therein with an inlet and an outlet, a valve seat member mounted in the larger 45 bore and provided with two seats of different diameters, a valve reciprocally mounted in said larger bore having two seat portions and adapted to engage the two seats in said seat member, said valve having a stem extending 50 from one end, a piston secured to the valve stem of said valve and reciprocally mounted in the smaller bore in said casing and on the opposite side of the outlet in said casing from the valve, a by-pass through said valve and 55 stem from between the two seat portions in said valve to the portion of said smaller bore

on the side of the piston farthest from the valve.

4. In a throttle valve for steam engines, a casing provided with three diameter bores and 60 an inlet and an outlet, a valve stem reciprocally mounted in the smallest diameter bore, a piston secured to said valve stem and reciprocally mounted in the intermediate bore, a valve member in the largest bore secured to 65 said valve stem and spaced from said piston and on the opposite side of the outlet in said casing from said piston, said valve provided with two seat portions of different diameters, the seat portion of smaller diameter being substantially equal to the diameter of said piston, and a valve seat member in said casing 70 having two valve seats of different diameters adapted to engage the respective valve seat portions on said valve. 75

5. In a throttle valve for steam engines, a casing provided with three diameter bores and an inlet and an outlet, a valve stem reciprocally mounted in the smallest diameter bore, a piston secured to said valve stem and reciprocally mounted in the intermediate bore, a valve member in the largest bore secured to 80 said valve stem and spaced from said piston and on the opposite side of the outlet in said casing from said piston, said valve provided with two seat portions of different diameters, the seat portion of smaller diameter being substantially equal to the diameter of said piston, a valve seat member in the said casing having two valve seats of different diameters adapted to engage the respective valve seat portions on said valve, and a conduit in said valve and said valve stem extending from between the two seat portions 85 on said valve to the portion of the intermediate bore on the side of the piston farthest from the valve. 90

6. In a device of the class described, a casting provided with a bore, an inlet, an outlet, and a pair of concentric valve seats in said bore, spaced axially from each other and positioned between the inlet and the outlet, a valve reciprocally mounted in the bore and provided with a pair of valve portions adapted to simultaneously engage the valve seats in said bore, and a piston portion connected to said valve on the opposite side of the outlet. 100

In testimony whereof, I have hereunto set my hand at Los Angeles, California, this 10th day of May, 1926.

RUSSELL R. WATERMAN.
